UNITED STATES PATENT OFFICE.

CHARLES E. NUTTING, OF HOPEDALE, MASSACHUSETTS, ASSIGNOR TO DRAPER CORPORATION, OF HOPEDALE, MASSACHUSETTS, A CORPORATION OF MAINE.

FILLING-END CATCHER FOR LOOMS.

1,394,637.

Specification of Letters Patent.

Patented Oct. 25, 1921.

Application filed October 2, 1918. Serial No. 256,581.

To all whom it may concern:

Be it known that I, CHARLES E. NUTTING, a citizen of the United States, residing at Hopedale, county of Worcester, State of Massachusetts, have invented an Improvement in Filling-End Catchers for Looms, of which the following description, in connection with the accompanying drawing, is a specification, like characters on the drawing representing like parts.

This invention relates to improvements in automatic filling replenishing looms and its object is to provide a simplified means which can be readily applied to a usual form of loom for catching and retaining the trailing end of the filling running from an abandoned filling carrier after its discharge from the shuttle by the transferring mechanism so that the filling end will not be caught and carried by the shuttle or the freshly inserted filling carrier into the cloth upon the succeeding pick.

This object is accomplished in the present invention by yieldably supporting from a stationary part of the loom, desirably the transerrer stud, a preferably flexible plate having a filling engaging member, which is so positioned that it will approach, and preferably engage, the rear wall of the aperture in the lay through which the abandoned filling carrier is discharged as the lay beats up, then as the lay recedes after the filling carrier has been discharged will catch the trailing filling end and pull it from the eye of the shuttle.

A further object of the invention is to provide an improved means for supporting the filling end catcher in which the resilient means for retaining the catcher in a normal extended position will be wholly inclosed so that its operation will not become impaired by accumulation of lint or other detritus.

A further object of the invention is to provide means for adjustably positioning the filling end catcher which will not modify its dust excluding character.

Other objects and features of the invention will more fully appear from the accompanying description and drawings and will be pointed out in the following claims.

In the drawings:

Figure 1 is a side elevation of a sufficient portion of the battery end of a loom of the well known Northrop type to illustrate the application of the present invention thereto.

Fig. 2 is an end elevation partly in vertical cross section of the same.

Fig. 3 is a detail plan view of a preferred form of filling end catcher embodying my invention, and,

Fig. 4 is a detail sectional view on lines 4-4 Fig. 3.

The present invention is addressed to improvements in mechanisms for catching the trailing end of filling running from the abandoned filling carrier as it is discharged from the shuttle and is not concerned with the particular construction or operation or the general features of the loom to which it is applied. For convenience in illustration a preferred embodiment of my invention is shown as embodied in an automatic filling replenishing loom of the well known Northrop type. In this type of loom the frame or loom side 1 supports at the transfer end of the loom a hopper stand 2 upon which is mounted a rotary hopper 3 which carries a circular series of fresh filling carriers 4. The stand 2 has the usual laterally extending transerrer stud 5 upon which the transerrer 6 is pivotally mounted and the transerrer is provided with the usual dog 7 which, upon call for filling replenishment, is elevated into the path of the bunter 8 carried by the lay 9.

The engagement of the bunter 8 upon the moving lay and the dog 7 of the transerrer oscillates the transerrer to cause its head to thrust a fresh filling carrier from the hopper into the shuttle and drive out the abandoned filling carrier which is until that time retained in the jaws of the shuttle.

The lay 9 has the usual shuttle box 10 and the shuttle box and lay are provided with a vertical aperture 11 through which the filling carrier is discharged from the shuttle by the transerrer.

A chute 12 which is carried by an arm or bracket 13 secured to the end of the lay by a suitable bolt 14 serves to direct the abandoned filling carrier 15 into the usual receptacle.

Filling replenishing looms customarily comprise means operable in conjunction with the transferring mechanism for cutting and clamping the filling leading from the cloth to the filling carrier about to be discharged closely adjacent the eye of the shuttle. When therefore the filling carrier is discharged from the shuttle it is neces-

sary to draw the severed and trailing filling end through the eye of the shuttle and away from the shuttle before the shuttle is sent through the shed upon the next pick 5 succeeding transfer, otherwise the trailing filling end is likely to be drawn into the web of cloth where it will produce a defect in the weave.

I am aware that various means have been 10 provided for catching such trailing filling ends and the present invention is intended to provide a simple construction which may be readily applied to a usual form of loom without requiring modification of the loom 15 structure, which will be dust proof and in which the parts are so constructed that they will not be likely to become broken or loosened during the operation of the loom.

In the preferred embodiment of the invention 20 disclosed herein the filling catcher comprises an integral flexible plate of resilient material which preferably is of L-shaped form comprising a member 16 having a toothed or serrated upper edge 17 and a member 18 which is slidably mounted in a guideway 20 between complementary sections 21, 22 of a bracket 23 having at its upper end a boss 24 bored horizontally to receive and fit a supporting rod 25 which 30 may be carried by any stationary portion of the loom frame but preferably is connected to the lower end of an arm 26 which has at its upper end a boss 27 secured upon the transerrer stud 5 by a set screw 28 or other 35 suitable means. In such construction the adjustability of the arm 26 about the transerrer stud 5 and the adjustment of the bracket 24 about the stud 25 provides means whereby the filling end catcher 16 may be 40 adjusted both vertically and horizontally so that the catcher may be positioned in any desirable relation to the lay and the path of the shuttle.

Furthermore the construction is such that 45 the bracket 23 may be adjusted longitudinally of the lay upon the stud 25 so that the filling end catcher may be held in any desired position.

In the operation of the loom the lay does 50 not always stop in exactly the same position upon its beat-up. It is however desirable that the filling end catcher should engage upon every beat-up the rear wall of the aperture in the lay through which the abandoned filling carrier is discharged. Means therefore are provided for yieldably supporting the filling end catcher.

In the illustrative embodiment of the invention disclosed herein the member 21 of 60 the bracket 23 which supports the filling end catcher desirably is in the form of a flat plate while the complementary member 22 of the bracket contains a recess which forms the guideway 20 for the filling end catcher.

These complementary members may be formed in any suitable manner to provide a suitable support for the filling end catcher and a closed housing for the spring which retains the filling end catcher in normal extended position.

The member 22 as illustrated herein desirably is provided with a hollow box-like housing 29 which is closed at both ends and in conjunction with the member 21 of the 75 bracket forms a closed chamber for the helical spring 30 which serves to hold the filling end catcher in normal, or extended, position.

One end of the spring 30 abuts against 80 the inner wall 31 of the housing while the opposite end 32 of the spring engages an offset end portion 33 of the member 18 of the filling end catcher. By reason of this construction the filling end catcher may be 85 stamped or forged from a plate by a very simple operation and when assembled in the bracket will provide a construction which is free of joints and the consequent likelihood of loosened parts. Furthermore the 90 construction is such that dust, lint and other foreign materials are entirely excluded from the chamber in which the spring is located which maintains the filling end catcher in normal extended position. Thus obstruction 95 to the proper operation of the filling end catcher is avoided.

In the operation of the loom filling carriers occasionally are improperly discharged so that they may be caught between the rear 100 wall of the lay as it moves forward and the filling end catcher or the filling carrier may be thrust by the bunter or other moving part against the filling end catcher. By constructing the filling end catcher therefore of 105 flexible, resilient plate, the likelihood of a smash, which might be occasioned by any of these conditions, is avoided.

It will be understood that the embodiment of the invention disclosed herein is of an 110 illustrative character and is not restrictive and that various modifications in form and construction may be made within the meaning and scope of the following claims.

Having thus described my invention what 115 I claim as new and desire to secure by Letters Patent is:

1. In a filling replenishing loom comprising a lay having an aperture therethrough to permit the discharge of an abandoned filling carrier and having a stand provided with a transerrer stud and a transerrer mounted thereon, a bracket carried by said transerrer stud comprising complementary members forming a closed housing, a filling 125 end catcher comprising a flexible plate formed of resilient material having a member adapted to engage the rear wall of the aperture in the lay as the lay beats up and a member having an offset end extending into 130

- said housing, a spring inclosed in said housing engaging the offset end of said member and acting normally to retain the filling end catcher in projected position but adapted 5 to permit said filling end catcher to yield bodily whereby a smash will be prevented if an obstruction is caught between the filling end catcher and the lay as the latter beats up.
- 10 2. In a filling replenishing loom comprising a lay having an aperture therethrough to permit the discharge of an abandoned filling carrier and having a stand provided with a transerrer stud and a transerrer mounted 15 thereon, an arm rotatably adjustable upon and depending from said transerrer stud, a stud extending from the lower end of said arm in parallelism with the lay, a bracket adjustable rotarily and longitudinally on 20 said stud and a filling end catcher mounted in said bracket whereby said filling end catcher may be properly positioned in re-
- spect to the lay but adapted to yield if an obstruction is caught between the filling end catcher and the lay as the latter beats up. 25
3. Filling end catching mechanism for automatic filling replenishing looms comprising a bracket adapted to be adjustably secured to a stationary part of the loom formed of complementary sections which when assembled provide a closed box-like housing and a guideway, an integral L-shaped plate of resilient flexible material, one member of which is provided with means for engaging the trailing filling end and the other member of which is slidably mounted in said guideway and provided with an offset end and a spring within said closed housing engaging the offset end of said plate within said housing and acting to maintain the 40 plate in extended position. 35

In testimony whereof, I have signed my name to this specification.

CHARLES E. NUTTING.
